UNITED STATES PATENT OFFICE.

HENRY FLYNT, JR., OF ST. LOUIS, MISSOURI, ASSIGNOR, BY MESNE ASSIGNMENT, TO HIMSELF AND DUDLEY H. FLYNT, OF SAME PLACE.

OIL-CAN.

SPECIFICATION forming part of Letters Patent No. 240,244, dated April 19, 1881.

Application filed May 20, 1880. (No model.)

To all whom it may concern:

Be it known that I, HENRY FLYNT, Jr., of St. Louis, State of Missouri, have invented a new and useful Improved Oil-Can, of which the following is a specification.

My invention relates to improvements in oil-cans or tanks in which oil is stored for dealers' uses and retail purposes.

According to my improvements the usual metal strip employed at the top of the can, in front thereof, serves here a twofold function: first, to form the bead or slat to support the lower edge of the cover when it is closed; secondly, said bead incloses the flanged edge of the top face where same is united to the angular top edge of the body of the can. The cover, in fully closing, has its lower edge passing over the vertical curvilinear face of the metal strip and rests upon the bead thereof.

My invention also relates to the manner of constructing and arranging the pump so that it can have a partial turn movement, also be readily removed or replaced, and be better adapted to empty oil-barrels, all of which will hereinafter be pointed out in the claims.

Of the drawings, Figure 1 is a transverse sectional elevation, showing the cover in full open condition, also showing the bead in front and top of can, also showing in side elevation the pump with its discharge-pipe turned inward.

Fig. 2 is a perspective view of the top parts of the oil-can. Fig. 3 is a top view simply of the circular rim and flange, (the latter being the pump-seat,) and forming part of the top face of the can, Fig. 4 being a bottom view of that part of the pump resting on the seat. Fig. 5 is an enlarged detail section, the better to show the bead made by joining the metal strip to the flanged edge of the top face. Fig.

6, Sheet II, shows the pump properly seated in the top face and can proper, the parts shown in section being the funnel of the pump, the rim, flange or seat, and opening in the top face of can.

A represents the body of the oil-can. As shown in Figs. 1, 2, 6, the oil-can is a plain top-faced can, in contradistinction to oil-cans having a top chamber or "pan," or a hinged leaf, and which are well known.

A' is the top face of the can. Said face has

its outer edge simply lapped over the flanged edge of the body of the can, as shown at a. (See Figs. 1, 5, and 6.)

B is the separate strip of metal, of proper length, size, and shape to constitute the front half and vertical curvilinear face top of the can. (See Figs. 1, 2, 5, and 6.) The lower edge of the metal strip B, I bend over or lap it to be the bead d. (See Figs. 1, 2, 5, 6.) It is this bead b that fits over and incloses the projecting flange-joint a, and as more clearly shown in Figs. 1, 5, 6. The joint of the top face and body of the can is therefore at the front half of the top of can covered, strengthened, and protected by the bead b of the strip B when same is soldered in place. The remaining portion of the metal strip B is left to be a vertical face half round the top part of the can, (instead of making the front body part of the can to extend to the same height above the top face.) Also, be it noted, it is the bead b that forms the needed slat upon which the front lower edge of the cover directly rests when same is in closed condition. Thus the bead b protects the rim or flange-joint a by covering it half-way round the can; secondly, the bead receives and supports the cover of the can when closed. The vertical face of the strip B can be crimped or corrugated. (See Fig. 2.) The upper edge of the strip B can be lapped, as indicated at b' in Figs. 1, 5, 6. By making the separate strip B to fit over and join the edges uniting the top face to the can, as above described, no wire need be left in the lapped edge, as ordinarily done, a saving in time and labor is achieved, nor need the best quality of material be used to compose the said separate strip B.

C represents the cover in its entirety. The constructive shape of the cover C is as shown in Figs. 1 and 2—that is, composed of the back c, the half-round front face, c', the inclined and curved front at c'', and the top at c''. So made I hinge the cover at c'' diametrically in the center of the top face of the can. When the cover is in full closed condition its front face, c', has its lower edge passed outside the vertical face of the strip B and rests upon the bead b, as previously stated. When the cover is in full open condition, as shown, it will be seen that

the back e rests fully upon the remaining half of the top of the can; hence the back of the cover is the better supported and protected. I also achieve the advantages of being enabled 5 to place under the cover the different measures used, such as gallon, quart, &c.; also, the pump can remain in the can, and all without interfering with the full opening or closing action of the cover.

10 The pump D consists of a pump-barrel containing a piston and its stem, operating as usual. D' is the discharge-pipe. The pump-barrel I make of different diameters—viz., to be of a small or upper section, d , and the larger 15 or lower section, d' . (See Figs. 1, 2, 4, 6.) The purpose of the smaller barrel d is to afford the pump more play when same is placed in the bung-hole of an oil-barrel, and hence permitting the lower or larger barrel, d' , to reach near 20 to the end of the oil-barrel—in other words, the pump can be set at an inclination in the barrel for the better emptying of same.

The seating of the pump D in the oil-can is as follows: The top face has the opening e , 25 through which the main part of the pump passes, as indicated in Figs. 1, 3, 6. The opening e at e' has a slit. At e^2 the metal (of the top face) surrounding the opening forms a flange or seat, and said seat is surrounded by 30 a vertical rim, e^3 , all as shown in Figs. 1, 3, and 6. The upper section, d , of the pump has forming part of it the funnel E, and this has its upper edge turned downward to form the circular rim e^4 . (See Figs. 4 and 6.) A

lug, e^4 , projects from the under side of the 35 funnel. Hence, as apparent, when said lug is passed through the slit e' , the pump, by its circular rim e^3 , bearing upon the seat e^2 , can be turned either way to vary the position of its discharge-pipe. The pump can be easily removed from or replaced in the oil-can. 40

What I claim is—

1. The oil-can consisting of the body A, its top face, A', lapped over the flanged face of the body, the separate metal strip B, having its 45 lower bead, b , inclosing the joint of the top face to the body of the can, while the remaining portion of said strip constitutes the outer vertical curvilinear face, the cover C, consisting of the back e , the half-round front face, e' , 50 the inclined and curved front e^2 , and the top e^3 , said cover hinged centrally at e^4 , all said parts combined to operate as and for the purposes set forth.

2. The oil-can A, its top face, A', having 55 opening e , slit e' , flange or pump-seat e^2 , circular rim e^3 , the pump having unequal diameter of upper and lower sections, the funnel E, its circular rim e^4 , and cleat or lug e^4 , all said parts combined and arranged to operate as and for 60 the purposes set forth.

In testimony of said invention I have hereunto set my hand.

HENRY FLYNT, JR.
